Des. 222,324
Patented Oct. 19, 1971

222,324

HAIRBRUSH HANDLE

Dan E. Simon, 20142 Scottsdale Blvd.,
Shaker Heights, Ohio 44122

Filed May 14, 1970, Ser. No. 22,979

Term of patent 14 years

Int. Cl. D4—02

U.S. Cl. D4—35

FIG. 1

FIG. 2

FIG. 3

FIG. 4

FIG. 5

FIG. 6

FIG. 1 is a view in side elevation of a hairbrush handle embodying the design.

FIG. 2 is a view in elevation of the handle as seen from the opposite side of FIG. 1.

FIG. 3 is a top plan view of the handle.

FIG. 4 is a bottom plan view of the handle.

FIG. 5 is an end elevation of the handle as viewed from the left side of FIG. 1.

FIG. 6 is an end elevation of the handle as viewed from the right side of FIG. 1.

I claim:

The ornamental design for a hairbrush handle, substantially as shown.
